UNITED STATES PATENT OFFICE.

EDWARD RICHARD HUGHES, OF LIVERPOOL, ASSIGNOR TO F. & A. FOWNES,
OF WORCESTER, ENGLAND.

DESIGN FOR A BUTTON.

SPECIFICATION forming part of Design No. 24,445, dated July 2, 1895.

Application filed May 14, 1895. Serial No. 549,320. Term of patent 14 years.

To all whom it may concern:

Be it known that I, EDWARD RICHARD HUGHES, clerk, a subject of the Queen of Great Britain, residing at Liverpool, in the county of Lancaster and Kingdom of England, have invented and produced a new and original Design for a Button for Gloves and other Articles, of which the following is a specification, reference being had to the accompanying drawings, in which—

Figure 1 is a front view; Fig. 2, a section.

A is the button, which is circular in shape and has embossed ridges in the middle of its front face, which form a roughened surface B. Around the roughened surface B is an

annulus C, on which the maker's or seller's name or other matter is embossed. At the back of the button is the eye D for sewing it to the glove or other article.

What I claim is—

The design of a button for gloves, &c., substantially as shown and described.

In testimony whereof I have signed my name to this specification in the presence of two subscribing witnesses.

EDWARD RICHARD HUGHES.

Witnesses:

G. C. DYMOND,
W. H. BEESTON.
